UNITED STATES PATENT OFFICE

166,780

COOKING UTENSIL

William B. Watkins, Winnetka, Ill., assignor to
The Wm. B. Watkins Co., Evanston, Ill., a cor-
poration of Illinois

Application February 23, 1950, Serial No. 8,068

Term of patent 14 years

(Cl. D44—1)

To all whom it may concern:

Be it known that I, William B. Watkins, a citizen of the United States, residing in Winnetka, in the county of Cook and State of Illinois, have invented a new, original, and ornamental Design for a Cooking Utensil, of which the following is a specification, reference being had to the accompanying drawings, forming part thereof, in which:

Fig. 1 is a top plan view of a cooking utensil, showing my new design;

Fig. 2 is a side elevational view thereof;

Fig. 3 is an elevational view of the handle end thereof;

Fig. 4 is a fragmentary enlarged top plan view showing the handle and its union with the utensil body;

Fig. 5 is a fragmentary enlarged side elevational view showing such handle and union;

Fig. 6 is a fragmentary enlarged end elevational view showing such handle and union;

Fig. 7 is a bottom plan view of the utensil;

Fig. 8 is a fragmentary enlarged bottom plan view showing the handle and its union with the utensil body; and

Fig. 9 is a transverse sectional view taken on the line 9—9 of Fig. 7.

The dominant features of the design reside in the handle and connecting ferrule, the first being characterized by two longitudinally extended grooves along the upper and lower surfaces; the second by a generally rectangular cross-sectional form with notches extending to opposite sides in the upper and lower surfaces thereof, as shown.

I claim:

The ornamental design for a cooking utensil, substantially as shown and described.

WILLIAM B. WATKINS.
